UNITED STATES PATENT OFFICE.

EDWARD J. WEINERS, OF ALEXANDRIA, VIRGINIA.

PAPER-CUTTING MACHINE.

Application filed February 20, 1925. Serial No. 10,637.

This invention relates to a machine for cutting paper strips and more particularly to such a machine adapted for cutting blank forms with entries thereon whereby the individual entries may be filed in their proper places.

It is the practice of every railroad company to ship the cars of other railroad companies, such as refrigerating cars, over the same routes and these cars at frequent points are supplied with ice to maintain the perishable foods in the cars in proper condition. On a blank form provided for that purpose entries are made as to the name of the station at which the icing of the cars is done, the amount of ice used, etc. These forms are provided with standard headings and below the headings are provided with horizontal spaces in which the data referring to the individual cars is filled in each time the car is iced. After the trip is completed these forms are usually cut by hand on the horizontal lines dividing the horizontal spaces, and the strips thus cut are assorted according to the number of the car and the company to which the car belongs. This work is very tedious and consumes considerable time of a force of clerks provided for that purpose. In cutting the forms, the headings and such of the horizontal spaces as have not been used, are discarded and this work also is commonly done by hand.

An important object of the present invention is to provide a machine for cutting the forms referred to on the horizontal lines and automatically discarding the headings of the forms and the blank spaces at the bottom thereof.

A further object of the invention is to provide means for discarding such of the horizontal spaces of each individual form as have not been filled in.

A still further object of the invention is to provide a novel form of cutting means for separating the standard forms horizontally along the lines printed thereon.

A still further object of the invention is to provide cutting means including a roller having fixed spaced cutting edges corresponding in width to the spaces between the horizontal lines of the blank forms, means being provided for adjusting the position of the paper before feeding it to the cutting means to allow for variations in the widths of the headings.

A still further object is to provide a plurality of pivoted fingers arranged toward the outlet side of the cutting device, each of the fingers corresponding substantially to the width of the spaces between the horizontal lines of the forms and each being adapted to be raised to operative position to discard the horizontal spaces of the forms which have not been filled in.

A still further object is to provide novel means for controlling the movement of the discarding fingers referred to whereby certain of the horizontal spaces of the forms may be discarded.

Other objects and advantages of the invention will be apparent during the course of the following description.

In the drawings I have shown one embodiment of the invention. In this showing:

Figure 1 is a plan view of the machine,

Figure 2 is a section taken substantially on line 2-2 of Figure 3;

Figure 3 is a section on line 3-3 of Figure 1;

Figure 4 is a section on line 4-4 of Figure 3;

Figure 5 is a detail perspective of one of the pulley supporting members,

Figure 6 is a horizontal sectional view through one of the pulleys, a portion of the cable being shown in elevation,

Figure 7 is a side elevation of the machine,

Figure 8 is a detail perspective of one of the discarding fingers,

Figure 9 is a fragmentary perspective of one end of the cable supporting slide and bracket therefor,

Figure 10 is a section on line 10-10 of Figure 7,

Figure 11 is a view of one of the forms in connection with which the machine is adapted to be employed,

Figure 12 is a detail sectional view on line 12-12 of Figure 1, and,

Figure 13 is a similar view on line 13-13 of Figure 1.

Referring to the drawings, the numeral 10 designates as a whole a pair of preferably cast integral side frames, each of which includes upper and lower outstanding flanges 11 and 12 respectively. The frames may be provided with openings 13 to reduce the weight thereof, the upper and lower portions of each frame being connect-

ed at its forward and rear ends by webs 14 and 15 respectively, and at its central portion by a relatively wide web 16. The upper portions of the side frames are provided with substantially horizontal rear ends as shown in Figures 3 and 7 and the side frames are provided substantially throughout these horizontal portions with machined grooves 17 for a purpose to be described.

As shown in Figures 1 and 3, a platen 18 is connected between the side frames and throughout the horizontal portions thereof. The platen is substantially equal in depth to the cuts made to form the shoulders 17 and are adapted to rest thereon as shown in Figures 12 and 13. It will be apparent that the upper surfaces of the flanges 11 and platen 18 will be flush as shown in Figure 12. Screws 19 are arranged to project through the edges of the platen and are threaded into the frames as clearly shown in Figure 13. It will be apparent that the screws 19 serve to secure the platen 18 to the side frames, while the platen properly spaces the side frames from each other. The platen may be provided on its upper face with guide lines 20 for a purpose to be described.

As shown in Figure 1, a pair of adjusting bars 21 are mounted over the platen 18 near opposite sides thereof. These bars are connected with screws 22, screw threaded in bosses 23 extending upwardly from the opposite ends of the horizontal portions of the frames, as shown in Figures 1 and 3. The screws 22 may be provided with enlarged heads 24 for convenience in manual operation. It will be apparent that by adjusting the screws 22, the bars 21 may be moved inwardly and outwardly.

As shown in Figures 3 and 7, the forward portions of the side frames slope downwardly toward their forward ends and these sloping portions of the frame are provided at their inner and upper corners with machined shoulders 25 formed similar to the shoulders 17 previously described. A bed plate 26 is adapted to rest on the shoulders 25 as shown in Figure 4 and this plate is provided at opposite sides with upturned flanges 27. The plate 26 is provided with a relatively large opening 28 for a purpose to be described. Rearwardly of the plate 26, a guard plate 29 extends across the machine, as shown in Figures 1 and 3. This plate is arranged above the plate 26 and the rear ends of the latter, outwardly of the opening 28, are turned upwardly against the bottom of the plate 29 as shown at 30 and 31 respectively. The side 30 of the plate 26 is provided with a stamped up groove 32 arranged substantially parallel to the side frame and has a curved portion 33 connected therewith and communicating

with a transverse portion 34 extending to the inner edge of the side 30. A plate 35 is arranged rearwardly of the plate 26 substantially in alignment therewith, and the rear edge of the plate 35 is spaced from the forward end of the platen 18 to provide space for the cutting means to be described. An outstanding flange 36 is connected beneath the rear edge of the plate 35 and extends slightly therebeyond for a purpose to be described.

As shown in Figures 3 and 7, the side frames are provided intermediate their ends with upwardly extending portions 37 each of which is provided with a vertical transverse cut-out portion 38 adapted to receive a bearing block 39. Each of the blocks 39 is provided with side flanges 40 adapted to engage against the outer side of the adjacent portion 37 and the bearing blocks are secured against the frame by screws 41 extending through the flanges 40. A shaft 42 is journalled in the blocks 39 and this shaft is provided upon one end, outwardly of the side frame, with a gear 43. A cutting roll 44 designated as a whole by the reference numeral 44 surrounds the shaft 42 intermediate the side frames, as shown in Figure 1. This roll includes a plurality of spacing members 45 between which are mounted circular cutting knives 46. Nuts 47 are arranged outwardly of the ends of the roll 44 to clamp the collars and cutting knives together, as will be apparent. The cutting knives 46 are spaced apart a distance equal to the parallel lines dividing the form to be described into horizontal spaces.

Arranged parallel to the shaft 42 below and to one side thereof is a second shaft 48 journalled in bearing openings 49 formed in the side frames. The shaft 48 is provided on one end with a gear 50 meshing with the gear 43, as shown in Figure 7. The shaft 48 carries a roller 51 which is arranged substantially in contact with the roller 44 and is provided with spaced circumferential grooves 52 to receive the cutting knives 46, as shown in Figure 3. A guard 53 is arranged between the side frames parallel to the shafts 42 and 48 and in proximity to the roller 51 and cutting knives 46.

A shaft 54 is threaded into one of the side frames as at 55 and is provided at its outer end with a pinion 56, meshing with the gear 50. A gear 57 is also carried by the shaft 54 outwardly of the gear 56, and meshes with a pinion 58 carried by a shaft 59 journalled in a bearing opening 60 formed in the side frame. The shaft 59 is provided inwardly of the side frame with a pulley 61 adapted to be driven by a suitable belt from any suitable source of power (not shown).

As shown in Figures 3 and 7, I provide means for properly spacing the side frames

- apart adjacent the cutting mechanism just described. As shown, a plurality of bars 62 extend between the side frames and are threaded at opposite ends to receive nuts 63 which are adapted to engage the inner faces of the side frames. The bars 62 are also provided with nuts 64 arranged adjacent their extreme outer ends and adapted to engage the outer faces of the side frames.
- 10 The forward ends of the side frames may be maintained in proper position by a brace 65 having upturned ends 66 riveted or otherwise secured as at 67 to the inner faces of the side frames.
- 15 A plurality of pivoted fingers 68 are mounted in the opening 28 of the bed plate 26, as shown in Figures 1 and 3. As shown in Figure 8, each of the fingers 68 comprises a flat strip of metal bent at one end to provide an eye 69. Each of the fingers is provided at opposite sides with small shoulders 70 whereby the outer end of the finger will be slightly reduced as at 71 to prevent the paper strips from binding against the edges of the fingers 68, as will be described. The fingers 68 are arranged in alinement with the spaces between the cutting knives 46, as shown in Figure 1 and a pin 72 passes through the eyes of the fingers to pivotally support them, as will be obvious. The opposite ends of the pin 72 may be mounted within openings formed in the side frames 10. The forward ends of the fingers 68 are adapted to rest upon the flange 36 as shown in Figure 3, whereby the upper faces of the fingers will be flush with the upper face of the plate 35.
- 20 Means are provided for selectively raising as many of the fingers 68 as may be desired.
- 25 As shown in Figures 2 and 3, I provide a continuous cable 73 to which is secured a plurality of balls 74 spaced apart a distance equal to the width of the fingers 68. A pair of brackets 75 are secured against the inner face of one of the side frames 10, as shown in Figure 2. Each of these brackets is provided with a depending portion 76 having openings 77 therein to receive screws or the like whereby the device may be secured against the side frame. The bracket 75 further comprises an upper horizontal leg 78 which is provided at its outer end with a depending stub shaft 79 upon which is journalled a pulley 80. A nut 81 is arranged on the lower end of each of the stub shafts 79 to support the pulleys 80 in position. As shown in detail in Figure 6 of the drawings, the pulley 80 at the forward end of the machine is provided with spaced substantially semi-spherical indentations 80' acting as sprockets to receive the balls 74 to permit them to pass around the pulley. The cable 73 is adapted to extend through openings 82 formed in one of the side frames 10, as shown in Figure 2. Pulleys 83 are
- adapted to support the cable outwardly of the frame and these pulleys may be secured beneath the flange 11 of the side frame. As shown in Figure 3 of the drawings, the balls 74 are adapted to pass through the grooves 70 32 and 34 from whence they move across beneath the fingers 68. A supporting strip 84 is arranged beneath and parallel to the fingers 68 and is adapted to support the balls 74 as the latter are moved across the 75 machine. Each end of the strip 84 is soldered or otherwise secured to a bracket 85 which extends forwardly and downwardly beneath the hinges of the fingers and is provided with an upwardly extending forward end 86 which may be soldered or otherwise secured beneath the bed plate 26. The cable 73 passes forwardly from the rear pulley 83 substantially parallel to the top of the side frame, as shown in Figure 7. The cable passes around a pulley 87 secured to the side frame and then downwardly and forwardly around another pulley 88 from whence it passes forwardly to the forward pulley 83. The pulleys 87 and 88 are provided to permit the portion of the cable rearwardly thereof to assume the horizontal position shown in Figure 7 and forwardly of the pulley 88 the cable passes between the shafts 48 and 54. 90
- 95 Means are provided for permitting the operator to properly locate the balls 74 when it is desired to discard some of the strips cut from the forms. As shown in Figure 7, a collar 89 is secured to the cable and is provided with an upwardly extending finger 90 having a pointer 91 secured to its upper end. The finger 90 passes through a slot 92 formed in an index plate 93, as shown in Figure 1. The index plate is 100 adapted to be secured against the upper face of the side frame between the bosses 23 thereof, by screws or the like 94. The plate 93 is provided with indicia 95 associated with marking lines 96 and from the right hand end of the plate 93 the indicia are numbered from zero up to the number of the cutting knives 46 and fingers 68. 105
- 110 As shown in Figure 3, the cutting elements may be covered by a guard 96 while the gearing previously described may be covered by a suitable housing 97, as shown in Figure 1. These elements are provided merely for the sake of safety, however, and may be omitted, if desired. 115
- 120 In Figure 11 of the drawings, I have shown a form adapted to be cut by the machine described. In this form a heading space 98 is provided at the top in which is printed the name of the fruit express company, as at 99, when the machine is used for cutting forms used for indicating the icing of refrigerating cars. The heading space 98 may be provided with any other suitable printing that may be desired, such 125

as the name of the company furnishing the ice, the date of the form, etc. Beneath the heading space a sub-heading space 100 is provided and extends horizontally across the sheet. In the sub-heading space there are provided suitable legends to indicate the information to be supplied in vertical columns formed by vertical lines 101. The form is further divided horizontally by lines 102 forming horizontal spaces 103 which may be numbered as at 104. The form is further provided with a blank space 105 extending across the bottom thereof. The information to be filled in on the form described, which it is desired to sort and file, is confined between a line 106 dividing the horizontal spaces from the subheading and a line 107 dividing the horizontal spaces from the space at the bottom of the sheet. It is the present practice to cut the sheet horizontally along the lines 106 and 107 and to discard the portions of the sheet outwardly of these lines. Any of the horizontal spaces 103 toward the bottom of the sheet which have not been filled in are also likewise discarded.

The operation of the machine is as follows: One of the forms as illustrated in Figure 11 is filled in with the desired information as the cars of the train are iced at successive icing stations. This data includes the car initial and number, the weight of the ice, etc. From the car initials and numbers the name of the railroad owning the car may be determined and it is desired to cut the forms along the horizontal lines 102 whereby the individual horizontal strips may be properly sorted and filed. As a rule, all of the spaces provided are not filled and consequently some of the horizontal spaces toward the bottom of the sheet will remain blank since the blank spaces are filled in on the sheet starting from the top thereof. The sheet is arranged on the platen 18 with the upper edge arranged toward the operating side of the machine, this being the side toward the index plate shown in Figure 1. The line 106 is arranged to coincide with the adjacent line 20 on the platen and the bar 21 is adjusted forwardly until it contacts with the edge of the sheet. With power applied to the pulley 61 to drive the rollers 44 and 51, the sheet is ready to be cut. The sheet is moved forwardly to contact with the roller 51 whereupon it rides up over the latter beneath the guard 53, to pass between the rollers 44 and 51. The knives 46 are adapted to cut on the horizontal lines 102 when the bar 21 has been properly adjusted. The sheet is passed continuously through the rollers until the cutting action has been completed. In practice the width of the opening 28 in the plate 26 corresponds to the distance between the lines 106 and 107 of the form. As previously stated, the sides

30 and 31 of the plate 26 are turned upwardly against the plate 29 as shown in Figure 3. It will be obvious therefore, that the portions of the form outwardly of the lines 106 and 107 will be deflected downwardly by the sides 30 and 31 of the plate 26, passing from the bottom of the machine to be discarded. If all the horizontal spaces 103 of the form are filled in, the pointer 91 is left in the position shown in Figure 1. Assuming that the last three spaces of the sheet are left blank, the pointer 91 is moved up to "3" on the index plate 93. The movement of the pointer 91 obviously moves the cable 73 and the first three balls 74 will be moved inwardly from the position shown in Figure 2 of the drawings whereby they will be arranged beneath the first three fingers 68, as shown in Figure 4 of the drawings. As the balls 74 pass beneath the fingers 68 at points relatively near the pivots thereof, it will be seen that relatively slight vertical movement need be imparted to the fingers to move the rear edges thereof to contact with the lower face of the plate 29. The strips passing from the cutters obviously pass between the plates 29 and 35 and the raised portions of the plate 26 and the raised fingers 68 will deflect downwardly portions of the sheets with which they come in contact. The portions of the sheet corresponding to the fingers 68 which are in normal position will pass thereover whereby they will be fed from the machine off the lower end of the plate 26 where they are collected by the operator to be sorted. As previously stated, the paper strips after being cut, pass between the plates 29 and 35 and the upper plate 29 is adapted to engage the paper to prevent it from being carried around the roller from its frictional contact with the sides of the cutting members. Thus, it will be seen that the strips will be fed between the plates 25 and 39 positively to be discarded or fed from the machine off the lower end of the plate 26. It will be obvious that the strip 84 supports the cable 73 in a position parallel to the lower faces of the fingers 68 when the cable passes thereunder. I prefer to provide the reduced ends 71 of the fingers to prevent any binding action between the paper strips and the edges of the fingers. Obviously the lowermost horizontal strip of the sheet which is filled in must pass by the edge of the adjacent raised finger and the provision of the reduced ends of the fingers prevents any binding action as the lowermost strip is fed from the machine. In the printing of the forms, the upper and lower edges thereof are found not always to be parallel. In the printing process, the sheet is sometimes lined up with the printing plate from the top thereof and sometimes from the bottom. When the sheet is lined with the top of the printing plate,

the upper edge of the sheet previous to the cutting operation is arranged against the bar 21 toward the operating side of the machine. If it has been found, however, that the top 5 edge of the sheet is not parallel to the horizontal lines of the sheet, the opposite bar 21 may be moved forwardly to serve as the guiding means. The plurality of lines 20 are provided for convenience in alining the 10 horizontal lines of the sheet, as will be obvious.

Particular attention is invited to the arrangement of the rollers 44 and 51, as shown in Figure 3 of the drawings. It has been 15 found that if these rollers are arranged in vertical alinement, the paper contacts first with the cutting knives without being arranged in contact with the roller 51 and a very inferior cutting action is obtained. I 20 have found that with the rollers arranged in the peculiar relation shown in Figure 3, with the roller 51 nearer the platen 18, a very sharp accurate cutting action may be obtained.

25 While I have described the machine as being particularly adapted for use in connection with a particular kind of blank form, it will be obvious that it is adapted for use with forms of any other nature for cutting 30 a sheet into a plurality of strips.

It is to be understood that the form of my invention herewith shown and described is to be taken as a preferred example of the same and various changes in the shape, size 35 and arrangement of parts may be resorted to without departing from the spirit of the invention or the scope of the subjoined claims.

I claim:

40 1. In a paper cutting machine, means for cutting a sheet of paper into a plurality of pieces, means associated with and arranged adjacent said cutting means and receiving pieces of paper directly therefrom for selectively assorting all of said pieces, and means for operating said last named means.

45 2. In a paper cutting machine, means for cutting a sheet of paper into a plurality of strips, and manually controlled means associated with and arranged adjacent said cutting means and adapted to receive the paper strips directly therefrom for selectively assorting said strips.

50 3. In a paper cutting machine, means for cutting a sheet of paper into a plurality of strips, a plurality of selecting members associated with and arranged adjacent said cutting means and adapted to engage the strips after they have been cut to selectively assort them, and means for operating said selecting members.

55 4. In a paper cutting machine, means for cutting into a plurality of strips a sheet of paper fed thereinto from one side thereof, and a plurality of fingers arranged on the

opposite side of said cutting means, said fingers being pivotally mounted at one end and having their free ends arranged toward said cutting means, the free ends of said fingers corresponding in arrangement to the strips and adapted to be selectively arranged above and below the line of discharge of said strips. 70

5. In a paper cutting machine, means for cutting into a plurality of strips a sheet of paper fed therein from one side thereof, a plurality of fingers arranged on the opposite side of said cutting means, said fingers being pivotally mounted at one end and having their free ends arranged toward said cutting means, the free ends of said fingers corresponding in arrangement to the strips and being normally arranged below the line of discharge thereof from said cutting means, and means for selectively raising the free ends of certain of said fingers above the line of discharge of the strips. 75

6. In a paper cutting machine, means for cutting into a plurality of strips a sheet fed therein from one side thereof, a plate arranged on the opposite side of said cutting means below the line of discharge of the paper strips therefrom and provided with an opening, and a plurality of fingers corresponding in arrangement to the strips 95 passing from said cutting means arranged in said opening and having their upper faces normally flush with the upper face of said plate, said fingers being pivoted at one end and having their free ends arranged toward said cutting means and adapted to be raised above the line of discharge of the strips from the said cutting means. 100

7. In a paper cutting machine, means for cutting into a plurality of strips a sheet fed 105 therein from one side thereof, a plate arranged on the opposite side of said cutting means below the line of discharge of the strips therefrom and provided with an opening, a plurality of fingers corresponding 110 in arrangement to the strips passing from said cutting means arranged in said opening and having their upper faces normally flush with the upper face of said plate, a hinge pin arranged beneath said 115 plate, said fingers being pivotally connected at one end to said pin and having their free ends arranged toward said cutting means, and means for supporting the free ends of said fingers in normal position, the free 120 ends of said fingers being adapted to be raised above the line of discharge of the strips from said cutting means.

8. A machine constructed in accordance 125 with claim 7 provided with manually controlled means for raising the free ends of said fingers.

9. A machine constructed in accordance 130 with claim 7 provided with means arranged beneath and movable across said fingers

from one side thereof for successively raising the free ends of said fingers.

10. A machine constructed in accordance with claim 7 provided with means arranged beneath and movable across said fingers from one side thereof for successively raising the free ends of said fingers, and means for indicating the position of said raising means.

11. In a paper cutting machine, means for cutting into a plurality of strips a sheet of paper fed therein from one side thereof, a plate arranged on the opposite side of said cutting means below the line of discharge of the strips therefrom, and provided with an opening, a plurality of fingers arranged parallel to the direction of discharge of and corresponding in arrangement to the strips from said cutting means, said fingers being arranged in said opening and having their upper faces normally flush with the upper face of said plate, said fingers being pivotally mounted at one end and having their free ends arranged toward said cutting means, a cable arranged beneath and movable across said fingers from one side thereof, and a plurality of lifting members carried by said cable, said lifting members being spaced apart a distance equal to the width of each of said fingers and adapted to lift the free ends thereof above the line of discharge of the strips from said cutting means.

12. A machine constructed in accordance with claim 11 provided with means for indicating the position of said lifting members.

13. A machine constructed in accordance with claim 11 provided with a handle for actuating said cable to progressively bring said lifting members into engagement with said fingers.

14. A device constructed in accordance with claim 11 provided with means for supporting said cable and said lifting members as they pass beneath said fingers.

15. A machine constructed in accordance with claim 11 provided with a handle for actuating said cable to progressively bring said lifting members into engagement with said fingers, and means associated with said handle for indicating the position of said lifting members.

16. In a paper cutting machine, a platen, a pair of rollers arranged adjacent one end of said platen, one of said rollers being provided with a circular cutting knife, the other of said rollers being arranged adjacent

said cutting roller and provided with a groove adapted to receive said knife, said last named roller being arranged nearer the platen than the other roller, and means for simultaneously rotating said rollers.

17. A machine constructed in accordance with claim 16 provided with a guard arranged adjacent said grooved roller, the paper from said platen being adapted to pass between said guard and said grooved roller to be fed upwardly at a relatively slight angle to pass between said rollers.

18. In a paper cutting machine, a platen adapted to support a sheet of paper having parallel lines thereon, a pair of rollers arranged adjacent one end of said platen, one of said rollers being provided with a plurality of circular cutting knives, the other of said rollers being provided with a plurality of circular grooves receiving said knives, said last named roller being arranged nearer to said platen than said first named roller, means for simultaneously rotating said rollers, the paper from said platen being adapted to pass between said rollers to be cut into strips by said knives along the lines on the paper, and means associated with said rollers for saving and discarding certain of said strips.

19. A machine constructed in accordance with claim 18 wherein said last named means includes a plurality of pivoted fingers corresponding in position to the spaces between said knives and having their free ends movable above and below the line of discharge of the paper strips from said rollers, and guide means associated with said platen for positioning the paper thereon with the lines of the paper in alinement with said knives.

20. In a paper cutting machine, a substantially horizontal platen, a pair of rollers arranged adjacent one end of said platen, one of said rollers being provided with a plurality of spaced circular cutting knives, the other of said rollers being provided with a plurality of circular grooves adapted to receive said knives, a pair of plates arranged to the opposite side of said rollers, said rollers being adapted to discharge a sheet of paper cut thereby between said plates, and means associated with one of said plates for saving and discarding certain of said strips.

In testimony whereof, I affix my signature.

EDWARD J. WEINERS.
